OPERATING KNOB AND ESCUTCHEON
PLATE ASSEMBLYHerbert M. Reeves, Kankakee, Ill., assignor to
Florence Stove Company, Gardner, Mass., a
corporation of Massachusetts

Application July 14, 1943, Serial No. 494,632

5 Claims. (Cl. 137—111)

1

The present invention pertains to a novel construction of knob and escutcheon plate or bezel for an operating stem projecting through a hole in a panel.

The general object of the invention is to reduce the cost of manufacture of constructions in which a knob, backed by an escutcheon plate, is mounted on an operating stem protruding through a fairly large hole in a panel filled by the escutcheon plate, and particularly by obviating the necessity of accurately aligning the stem in the center of the panel hole.

More particularly, it is an object of the invention to provide an arrangement of the general class indicated in which the escutcheon plate or bezel and the knob are constituted as structurally separate parts fixed together by a connection affording a relative lateral floating motion between the two.

Further objects and advantages of the invention will become apparent as the following description proceeds, taken in connection with the accompanying drawing, in which:

Figure 1 is a fragmentary front view of a portion of a burner box panel of a stove through which operating stems for gas cocks project that are equipped with knob and escutcheon plate assemblies embodying the present invention.

Fig. 2 is a transverse sectional view taken substantially along the line 2—2 in Fig. 1.

Fig. 3 is an exploded perspective view showing the end of one of the operating stems and the parts of the knob and escutcheon plate assembly associated therewith.

The invention is especially applicable to the front panel and associated operating stems of the gas cocks in a gaseous fuel cooking stove. As herein shown, 10 designates a portion of the front panel of a burner box for such a stove. The panels are usually made of sheet steel covered by porcelain enamel. Projecting through large round holes 11 in the panel, in the usual manner for such burner boxes, are operating stems 12 for gas cocks (not shown) located behind the panel. The holes 11 are bordered by inturned flanges 13.

In accordance with the present invention, each of the stems 12 is equipped with a novel knob and escutcheon plate assembly, and since those for the two stems shown are identical, a description of one will suffice for both. But three parts are required in the exemplary construction shown, these being a knob 14, an escutcheon plate or bezel 15 and a washer 16. Both the knob and escutcheon plate may be made of mold-

2

ed plastic material or synthetic resin and, if desired, may be made of the same shade of material so that they have the appearance, when assembled, of being but one piece.

To fix the knob or finger piece 14 removably on the end of the operating stem 12, the latter is provided with a flattened side at 12a to present what is known as a D-end, and a complementally shaped recess 14a is formed in the rear face of the knob 14. This recess is dimensioned so that the end of the stem telescopes within it with a snug friction fit, retaining the knob against inadvertent removal from the end of the stem.

The washer 16 also has a D-shaped opening 16a therein, complemental to the D-end on the operating stem 12, so that it can be slid onto the same and, when in place, will be fixed against rotation. The washer bears against a shoulder 12b at the inner end of the flattened slide 12a of the operating stem 12.

The escutcheon plate 15 is sandwiched between the washer 16 and a rearwardly facing shoulder on the knob herein formed by a laterally projecting flange portion 14b. The plate has a sufficiently large opening 15a in its center that a wide clearance is left between the edges of this opening and the telescoped portions of the knob and stem which are within it, thereby permitting a relative transaxial or floating movement 30 of the knob and escutcheon plate. The opening 15a is, however, completely hidden from view from the front of the assembly by the knob flanges 14b. The peripheral portion of the escutcheon plate 15 is round and is dimensioned to fit fairly accurately within the opening 11 in the panel 10 so as substantially to completely fill the same, the outer surface of the escutcheon plate being nearly flush with the panel. Such outer surface of the escutcheon plate may be provided with suitable indicia (not shown) for indicating the direction of opening, etc., for the gas cock which is operated by the stem 12.

The particular form of escutcheon plate shown is of shallow cup shape and its outer edge is rounded, as indicated at 15b, to enhance its appearance. On its inner face and integral annular rib 15c borders the central opening 15a and the edge of this rib is adapted to bear against the washer 16. Strengthening ribs 15d join the rib 15c to the annular wall about the periphery of the plate.

In assembling the construction shown, the primary advantage is that the operating stem 12 need not be accurately located with reference to the center of the panel hole 11. Elimination of

the necessity for accuracy of alignment at this point greatly simplifies the mounting of the burners in the burner box. With the operating stem 12 located only generally centrally of the panel hole 11, the illustrated escutcheon plate and knob assembly can be operatively mounted on it. For the latter purpose it is merely necessary to slip the washer 16, the escutcheon plate 15 and the knob 14 over the end of the operating stem in the order named.

When the parts are assembled as described, the escutcheon plate fits within and is centered by the edges of the panel hole 11, the plate being retained between the opposed surfaces of the knob 14 and washer 16. In the event that the stem 12 is not accurately centered with respect to the panel hole 11, the clearance in the hole 15a in the escutcheon plate, as well as the flat form of the opposed faces which hold the escutcheon plate, permits the escutcheon plate to shift trans- 20 axially of the knob.

The net result is that an assembly is provided on the end of the operating stem which includes an escutcheon plate or bezel that is located bodily within the panel hole, and may even be flush with 25 the face of the panel if desired, and yet substantial misalignment of the stem with respect to the center of the panel hole is permitted. In some instances it may be necessary or desirable that the escutcheon plate turn with the stem. In such 30 event, the plate is free to shift transaxially so as to avoid any danger of sticking or jamming of the parts.

I claim as my invention:

1. An operating knob and escutcheon plate assembly for use on an operating stem projecting generally centrally through a substantially larger hole in a fixed panel comprising, in combination, a knob adapted to be non-rotatably fixed to the projecting end of the stem, a washer on the stem, 35 an abutment on the stem adapted to hold said washer in spaced relation to the projecting end thereof, and an escutcheon plate disposed between the knob and washer and having a central opening for passage of the stem through it with 40 wide clearance about all portions of the projecting end of the stem and having a border portion peripherally dimensioned to fit accurately within the panel hole, said knob having a portion overlying and bearing against the front face of said 45 escutcheon plate and completely covering the opening in the plate, said knob being removable from the stem to allow installation of the plate after assembly of the stem with the panel.

2. The combination with a fixed panel having 50 a hole therein and an operating stem projecting generally centrally through said hole, of a knob removably held in non-rotatable relation with the projecting portion of said stem, an abutment on said stem in spaced relation to the rear face of 55 said knob, and an escutcheon plate having a central opening larger than any portion of the projecting end of the stem for loosely receiving the stem and covered by the outer portion of the knob, said escutcheon plate being interposed between the abutment and knob and being free for 60 limited movement transaxially of the latter, said escutcheon plate being disposed within and

dimensioned to substantially close the hole in said panel.

3. The combination with a fixed panel having a hole therein and an operating stem for a valve or the like, projecting generally centrally through the hole, of an operating knob on the forward end of the stem, a washer on the stem forming an abutment rearwardly of the knob, an escutcheon plate bearing upon said washer and having a central opening larger than any portion of the projecting end of the stem and loosely receiving the rear portion of the knob, said escutcheon plate being disposed within and dimensioned to close the hole in said panel, and a circular flange on said knob forwardly of the plate of a diameter substantially larger than the opening in the plate, said knob being removably secured to said stem to facilitate the assembly of said escutcheon plate with the stem and the panel.

4. The combination with a panel having a hole therein and an operating stem projecting generally centrally through said hole, of an operating knob on the forward end of the stem, said stem having a D-shaped forward end portion and said knob having a complementary recess to receive said D-shaped portion of the stem, a washer having a D-shaped hole therein to receive said projecting end of the stem, and an escutcheon plate having a central opening loosely receiving the rear portion of the operating knob and a rearwardly projecting peripheral flange bearing on said washer, said knob having a rearwardly facing shoulder disposed forwardly of the escutcheon plate and of a radial width such as to cover the opening in the plate.

5. An operating knob and escutcheon plate assembly for use on an operating stem projecting through a relatively large hole in a fixed panel comprising, in combination, a knob adapted to be frictionally secured to the projecting end of the stem in non-rotating relation, an escutcheon plate adapted to fit into the hole in the panel to close the same, said escutcheon plate having a central opening larger than any portion of the projecting end of the stem and adapted to receive the stem with a relatively loose fit whereby substantial misalignment of the stem within the panel hole is permitted, and a laterally projecting flange on said knob adapted to completely cover the opening in said escutcheon plate in any position of the stem within said opening, said knob being removable from said stem to permit installation of said escutcheon plate from the front of said panel.
